UNITED STATES PATENT OFFICE

JOSEPH ARTHUR CASIMIR BOIVIN, OF NASHUA, NEW HAMPSHIRE

ANTITHEFT DEVICE

Application filed July 29, 1929, Serial No. 381,860, and in Canada May 14, 1929.

The present invention pertains to a novel anti-theft device constructed particularly for use in connection with banks and similar institutions.

The object of the invention is to provide an apparatus for successfully combating the hold-ups which at the present are of such frequent occurrence. This object is accomplished by providing a mechanism which may be readily operated by the teller or clerk to completely close the front wall of his cage and at the same time lock the outer door to the banking room and sound an alarm.

In the accomplishment of this object, the open part of the front wall of the teller's compartment is provided with shutters adapted, when necessary, to form a solid closure. In this wall is also a wicket which may be closed by a sliding panel. Beneath the teller's cage is a shaft linked to the shutter and panel and also carrying a weighted lever. The weight of the lever normally rests on a rockable pedal on the floor and within easy reach of the teller. The parts are so arranged that when the pedal is operated in the event of a hold-up, the weight is left without support and caused to fall, whereupon the shutters and the wicket are immediately closed.

The door to the banking room is equipped with a latch which is operable by cables also connected to the shaft which is controlled by the weight. Thus the latch is locked when the pedal is operated, and the thief is consequently trapped. The latch may also be constructed to function as a switch for sounding an alarm when the latch moves into closed position.

The invention is fully disclosed by way of example in the following description and in the accompanying drawings in which

Figure 1 is a vertical section of the device, showing also in elevation a door operated thereby;

Figure 2 is a similar view showing the parts in locked position;

Figure 3 is a front elevation of the teller's cage, showing the wicket open;

Figure 4 is a similar view showing the wicket closed;

Figure 5 is a detail section of the shutter and associated parts in open position;

Figure 6 is a similar section showing the parts in closed position;

Figure 7 is a plan section of the operating mechanism;

Figure 8 is a plan section on the line 8-8 of Fig. 7; and

Figure 9 is a plan section of a modified multiple construction.

Reference to these views will now be made by use of like characters which are employed to designate corresponding parts throughout.

Figure 1 illustrates a banking room in which 1 a teller's counter with a wall 2 in front of the same. In line with the wall 2 and above the counter is an upper wall structure 3 corresponding to the usual cage. In the present instance this wall structure is in the nature of a shutter consisting of shutter strips 4 pivotally supported between vertical supports 5 and 6 as clearly shown in Figures 5 and 6.

On the lower face of the counter 1 is supported the teller's drawer 7 as shown more clearly in Figures 1 and 2. Beneath the shelf 1 are a pair of upright bearings 8 in which is journaled a shaft 9. To the shaft is fixed a rocker arm 10 carrying at one end a weight 11. The upper wall structure 3 has a wicket opening 12 which may be closed by a vertically slid able panel 13. The remaining end of the rocker arm 10 is joined to the lower edge of the panel by a link 14 as clearly shown in Figure 2.

To the shaft 9 are fixed two arms 15 near the bearings 8 as shown more clearly in Figure 7. Rocker members 16 are pivotally mounted at opposite sides of the shutter structure by means of hinges 16' on the framework 3 of the upper wall. The arms 15 are connected to the rockers by links 17 and 17' connected together by shaft 17" and the rockers are further connected to the slideable links 5 by links 18 as clearly shown in Figures 5 and 6. Thus, oscillation of the shaft 9 in the manner presently to be described operates the shutters and also the panel 13. The shutter operating mechanism

be placed between the ends of the adjacent shutter structures of adjacent cages as shown in plan section in Figure 8.

On the floor beneath the shelf 1 is secured a hinge member 20 to which is pivotally attached a pedal 21 having a foot piece 22. The member 21 carries at its upper end a roller 23 on which the weight 11 is adapted to rest as shown in Figure 1. When the parts 10 are in this position, the panel 13 and the shutters 4 are open. The member 21 is also formed with a rest 24 adapted to support the weight 11 as will presently be described.

The room containing the teller's cage is accessible through a double door consisting of door sections 25 and 26. The sections may be locked in closed position by a latch 27 pivoted on the section 26 and engageable in a keeper 28 on the section 25. The shaft 9 is still further provided with a bell crank lever 29 secured thereto, the ends of the lever being joined by cables 30 and 31 to the ends of the rocker latch 27. The cables are trained over and guided by pulleys 32 secured at suitable points. The cables contain electrical conductors (not shown) which are extended at 33 and 34 beyond the ends of the bell crank lever 29 and connected to the terminals of the battery 35. Conductors 36 and 37 are connected to the latch 27 and keeper 28 respectively, and joined to the terminals of an electric bell 38.

The parts are normally in the position shown in Figure 1, wherein the weight 11 is supported on the roller 23, the wicket 12 and shutters 4 are open and the latch at the door 25, 26 is unlocked. When an attempt is made to hold up the teller, he merely presses with his foot on the foot piece 22. This movement 40 tilts the pedal 21, whereby the roller is drawn from beneath the weight, and the latter falls on the rest 24. It will be apparent that the falling of the weight turns the shaft 9 and hence operates the shutter 4 and the panel 12 in the manner already indicated.

It will also be seen that the cable 30 is pulled downwardly and the cable 31 relieved, whereupon the latch 27 is carried into the keeper 28 as shown in Figure 2. The contact 50 of the members 27 and 28 closes a parallel circuit through the bell 38, whereby an alarm is given to summon help for the capture of the thief who has been trapped by the locking of the doors 25 and 26. At the same time the teller behind the closed shutters 4 and the money which now cannot be reached through the closed window 12, are protected.

In Figure 9 is illustrated a plan section of a multiple arrangement including a plurality 60 of cages or compartments 40, each of which contains a pedal 41 and operates beneath the teller's shelf similar to that already described. The door 42 corresponding to the previously described door 25, 26 is provided with a latch 43 which functions also as a switch. The

terminals of the switch are joined by conductors 44 and 45 to the terminals of a battery 46. A horn 47 disposed either within or outside the building is connected in series in the line 44, 45. When any one of the pedals 41 is operated, the switch 43 is closed and the alarm is given.

Although specific embodiments of the invention have been illustrated and described, it will be understood that various alterations in the details of construction may be made within departing from the scope of the invention as indicated by the appended claim.

What I claim is:

In an anti-theft device including a door structure, latch elements carried by relatively movable parts thereof, and cables for operating one of said elements, the combination of current conductors enclosed in said cables and joined to said elements respectively, and an alarm device in circuit with said conductors.

In witness whereof I have hereunto set my hand.

JOSEPH ARTHUR CASIMIR BOIVIN.
